UNITED STATES PATENT OFFICE.

LILLIAN GRANVILLE WALKER, OF BOSTON, MASSACHUSETTS.

DESIGN FOR A CORSET.

SPECIFICATION forming part of Design No. 30,381, dated March 21, 1899.

Application filed December 12, 1898. Serial No. 699,080. Term of patent 14 years.

To all whom it may concern:

Be it known that I, LILLIAN GRANVILLE WALKER, a citizen of the United States, residing at Boston, in the county of Suffolk and State of Massachusetts, have invented and produced a certain new, useful, and original Design for a Corset, of which the following is a specification, reference being had to the accompanying drawing, forming part thereof, 5
o in which the figure is an elevation of a corset embodying my new design, one-half of the corset being shown.

As shown in the drawing, the leading or material feature of my design is the configuration or shape of the bust edge d , waist edge a , and abdominal point b^2 . The waist edge a is provided with the reentrant openings a' and a^2 , one at each side of the flap portion a^3 . The back edge is marked b , and the front 5
o edge is marked b' . The abdominal point b^2 is formed by the downward curvature of the waist edge a meeting the front edge b' . The upper edge d is provided with reentrant openings d' d^2 , one at each side of the under bust flap portion d^3 . The front corner edge d^4 is 25 curved downward to the front edge b' .

Having described my invention, what I claim as new, and desire to secure by Letters Patent, is—

The design for a corset as herein shown 30 and described.

In testimony whereof I have signed my name to this specification, in the presence of two subscribing witnesses, on this 9th day of December, A. D. 1898.

LILLIAN GRANVILLE WALKER.
